UNITED STATES PATENT OFFICE.

BENJAMIN THOMAS SELMAN, OF CHATTANOOGA, TENNESSEE.

DESIGN FOR A CHARM.

SPECIFICATION forming part of Design No. 28,626, dated May 17, 1898.

Application filed January 25, 1898. Serial No. 667,939. Term of patent 7 years.

To all whom it may concern:

Be it known that I, BENJAMIN THOMAS SELMAN, a citizen of the United States, residing at Chattanooga, in the county of Hamilton and State of Tennessee, have invented and produced a new and original Design for a Charm; and I do hereby declare the following to be a full, clear, and exact description of the same, reference being had to the accompanying drawings, forming a part thereof.

Figure 1 is a perspective view showing the front of my newly-designed charm. Fig. 2 is a similar view of the back of the same. Fig. 3 is a cross-section.

The leading features of my design are the representation of a platform A, upon which is resting a carpenter's square B. The platform bears parallel lines to indicate the planks of which it is supposed to be composed. The

planks are numbered. The platform has a short leg *a* at each corner. The square B rests at its ends upon the platform, with its right-angled corner somewhat raised in order to show off the square to better advantage by making it more prominent. This elevation of the square is attained by upright flanges *b*, extending from the edges of the square to the platform.

Having thus described my invention, what I claim is—

The design for a charm, substantially as herein shown and described.

In testimony whereof I affix my signature in presence of two witnesses.

BENJAMIN THOMAS SELMAN.

Witnesses:

CALEB DEAN,
JNO. W. A. VARDAMAN.
